UNITED STATES PATENT OFFICE

139,768

DESIGN FOR A KITCHEN UTENSIL HANDLE

Herman Ray Ellinwood, Burbank, Calif., assignor
to Adel Precision Products Corp., a corporation
of California

Application March 21, 1944, Serial No. 112,975

Term of patent 14 years

(Cl. D44—29)

To all whom it may concern:

Be it known that I, Herman Ray Ellinwood, a citizen of the United States and residing at Burbank, in the county of Los Angeles and State of California, have invented a new, original, and ornamental Design for Kitchen Utensil Handle, of which the following is a specification, reference being had to the accompanying drawing, forming part thereof, in which:

Fig. 1 is a top plan view of a kitchen utensil handle showing my new design;

Fig. 2 is an elevational view showing one side of the handle;

Fig. 3 is a bottom plan view of the handle;
Fig. 4 is an elevational view of the other side of the handle;

Fig. 5 is an elevational view of one end of the handle;

Fig. 6 is an elevational view of the other end of the handle.

I claim:

The ornamental design for a kitchen utensil handle, substantially as shown.

HERMAN RAY ELLINWOOD.
